United States Patent Office

Des. 194,269
Patented Dec. 25, 1962

194,269

TRICYCLE

Clifford Harold Bessett, South Holland, Ill., assignor to
American Machine & Foundry Company, a corporation
of New Jersey

Filed Jan. 30, 1962, Ser. No. 68,569

Term of patent 14 years

(Cl. D34—15)

FIG. 1

FIG. 2

FIG. 1 is a front perspective view of a tricycle showing my new design; and

FIG. 2 is a fragmentary rear perspective view thereof.

The dominant features of my design reside in that portion shown in full lines of the drawing.

I claim:

The ornamental design for a tricycle, as shown and described.
